UNITED STATES PATENT OFFICE.

WAYNE E. DUNSTON, OF DETROIT, MICHIGAN, ASSIGNOR TO THE C. G. SPRING & BUMPER COMPANY, OF DETROIT, MICHIGAN, A CORPORATION OF DELAWARE.

BUMPER ATTACHING AND SUPPORTING MEANS.

Application filed May 8, 1923. Serial No. 637,463.

To all whom it may concern:

Be it known that I, WAYNE E. DUNSTON, a citizen of the United States, residing at Detroit, in the county of Wayne and State of Michigan, have invented a certain new and useful Improvement in Bumper Attaching and Supporting Means, of which the following is a full, clear, and exact description, reference being had to the accompanying drawings.

This invention relates to means for supporting bumpers from the frame members of automobiles, and has for its general object to provide a construction of supporting arm and of cooperating attaching means which will enable the said arms to be conveniently applied to the said members and to enable them, when so applied and secured, to support the bumpers in an efficient manner. I accomplish the foregoing objects by the construction illustrated in the drawings forming part hereof, wherein Fig. 1 represents a detail in perspective of the front of an automobile having my invention applied thereto; Fig. 2 a detail in plan showing a portion of a bumper and the cooperating supporting parts therefor; and Fig. 3 a detail in perspective of the rear or inner end of one of the supporting arms.

Describing the parts by reference characters, 1 indicates the radiator, 2 one of the side frame members, and 3 a cross brace or tube connecting the front of the said member with the front of the corresponding member on the opposite side (not shown). The front end of each side frame member will be provided with the usual hanger 4 having the eye 5 therein for the spring bolt, the said bolt being indicated at 6.

In the construction of automobile indicated herein, an apron or guard 14 of sheet metal covers the lower flange and the web of the channeled side member 2. In order to attach the bumper supporting arms to the front of the vehicle, the following construction is provided: 7 denotes one of the two arms by which the bumper 8 is supported (the bumper being of any suitable construction). The front or outer end of each arm 7 is provided with an eye 8 adapted to receive a bolt 9 by which it is connected to a clamp 10 on the adjacent portion of the bumper. Riveted to the arm 7, intermediate of its ends, is an upright 11, said upright having an aperture 12 therethrough which

is adapted to receive the spring bolt 6, whereby the intermediate portion of each arm 7 may be supported by such upright from the spring bolt. The rear or inner end of each arm 7 is notched downwardly from the top, as indicated at 7^a, to permit the lower portion to pass beneath the transverse brace 3 without unduly elevating the front or outer end of each such arm. Riveted to the rear or inner end of each arm is an angular bracket 13, the horizontal flange 13^a of which is provided with perforations 14 adapted to receive the ends of a U-bolt 15 which extends around the cross member 3, the lower ends of the bolt extending through the apertures 14 and being provided with nuts, one of which is indicated at 15^a.

By the construction shown and described herein, the bumper supporting arms may be conveniently applied to the type of automobile illustrated herein and, when so applied, will support the bumpers attached thereto in a very effective manner.

Having thus described my invention, what I claim is:

1. A bumper supporting arm having an intermediate supporting member attached to and projecting therefrom and having at its rear or inner end means for attaching the same to a cross member of an automobile.

2. A bumper supporting arm having intermediate of its ends a vertically extending projection provided with an aperture for the reception of a spring bolt and having at its rear end a bracket adapted to receive a U-bolt.

3. The combination, with the side member of an automobile and a cross member connected thereto, of a bumper-supporting arm, means securing the rear or inner end of said arm to said cross member, and means for supporting the intermediate portion of said arm from the said side member.

4. The combination, with the side member of an automobile having a spring hanger provided with an eye, and a cross member connected to said side member, of a bumper supporting arm, a projection intermediate the ends of said arm having an aperture therethrough, a spring bolt extending through said eye and said aperture, and means connecting the rear or inner end of said arm to said cross member.

5. The combination, with the side member of an automobile and a cross member con-

nected thereto, of a bumper supporting arm having a notch adapted to accommodate the said cross member, an angular bracket secured to the said arm, a U-bolt connected to said bracket and to said cross member, and means intermediate the ends of said arm for supporting the same from the said side member.

6. The combination, with the side member and a cross member of an automobile, of a bumper supporting arm having at its rear

end an angle bracket, a U-bolt connecting said bracket to said cross member, a spring hanger carried by the side member and having an eye for a spring bolt, a spring bolt in said eye, and a brace member projecting from the intermediate portion of said arm and mounted on said bolt. ¹⁵

In testimony whereof, I hereunto affix my signature.

WAYNE E. DUNSTON.
